DESIGN FOR A DRESS

Beatrice Chudnoff Kalish, New York, N. Y.

Application May 5, 1938, Serial No. 76,984

Term of patent 3½ years

To all whom it may concern:

Be it known that I, Beatrice Chudnoff Kalish, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

My design is characterized by the specific embroidery on the waist and sleeve portions of the dress as shown.

I claim:

The ornamental design for a dress, substantially as shown and described.

BEATRICE CHUDNOFF KALISH.
